UNITED STATES PATENT OFFICE

2,019,851

VERTICALLY MOVABLE DOOR OF THE TYPE
USED IN FREIGHT SHEDS AND ROUND-
HOUSES

Frederick William Hall, London, Ontario, Canada, assignor to Richards-Wilcox Canadian Company Limited, London, Ontario, Canada, a joint-stock company of Ontario

Application July 15, 1933, Serial No. 680,551
In Canada August 5, 1932

2 Claims. (Cl. 20—20)

My invention relates to improvements in vertically movable doors of the type used in freight sheds and roundhouses, and the object of the invention is to devise a door which may be operated manually with ease and at a fair rate of speed and open either partially or its height for the purpose of trucking or may be fully opened for the passage of larger vehicles or for trucking very large bulk articles, in which the hoisting device automatically adjusts itself to counterbalance the weight of the lower door section during its initial opening operation to an intermediate position and to counterbalance the weight of the entire door during the remainder of the opening operation, in which the raising of the door in a level plane is ensured, in which the operation of the doors puts the building superstructure to less stress than is entailed in the operation of doors of ordinary construction, in which the employment of an overhead track is obviated carried by the roof or roof trusses and the throwing of the doors out of alignment by the sagging of such roof structure, in which the doors when in the closed position are held tightly against the jambs and are unaffected by wind pressure and in which the reactions from wind pressure are evenly distributed to the building superstructure adjacent the door opening, and in which the door is rendered weather proof, and it consists essentially of the arrangement and construction of parts all as hereinafter more particularly explained.

Fig. 1 is an elevation of the door and door frame looking from the inside.

Fig. 2 is a vertical sectional view through the door and door frame showing the door in the closed position.

Fig. 3 is a similar view to Fig. 2 showing the lower door section raised to its intermediate position.

Fig. 4 is a similar view to Fig. 3 showing the lower door section further raised to unlock the upper door section and in the cam engaging position.

Fig. 5 is a similar view to Figs. 3 and 4 showing the door sections in the position they assume when the upper section is in the partially raised position.

Fig. 6 is a similar view to Figs. 3 to 5 showing the door sections in the fully raised position.

Fig. 7 is an enlarged plan sectional view through one side of the door frame and that portion of the door in engagement therewith.

Fig. 8 is an enlarged vertical sectional view

through the door intermediately broken away of its length at various points.

Fig. 9 is an enlarged view in front elevation of the hoisting mechanism.

Fig. 10 is a plan view of the parts illustrated in Fig. 9.

Fig. 11 is a further enlarged sectional view on line 11—11 Fig. 10.

Fig. 12 is a sectional view on the same scale as view 11 taken on line 12—12 Fig. 10.

In the drawings like letters of reference indicate corresponding parts in each figure.

1 indicates the door jambs which are in the form of channel iron located at each side of the door opening. 2 are columns H-shaped in cross section located to the outside of the jambs 1. 3 and 4 are horizontal bars formed of angle iron and extending between the columns 2 and to which the jambs 1 are connected. 5 and 5^x are angle bars extending between the angle bars 3 and 4 and spaced apart from the jambs 1. 6 is a centre angle bar extending between the angle bars 3 and 4 intermediately between the jambs 1.

7 and 8 are side guides secured to the jambs and forming the main guides for the door body. The door body is formed by two sections, a lower section 9 and an upper section comprising two portions 10 and 11 which are hingedly connected together at 12. The lower section 9 is provided with a guide roller 13. A guide roller 13 is located at each end of the door adjacent its bottom edge to operate within the side guides 7. The upper section of the door formed by the portions 10 and 11 is provided, at each end adjacent its bottom edge, with a roller 14 operating within the side guides 8. When the door is in the closed position the upper edge of the lower section 9 overlaps the lower edge of the portion 10 of the upper section.

15 are channel guides secured to the lower portion 10 of the upper door section. The guides 15 extend upwardly adjacent the face of the upper portion 11 but unattached thereto to project upwardly beyond the upper edge of the upper portion 11 as clearly illustrated in Fig. 1. The guides 15 are provided with upper and lower guide rollers 16 and 17 for a purpose which will hereinafter appear.

The lower door section is provided with upwardly projecting arms or horns 18 which extend into the guides 15, such horns being provided at their upper ends with rollers 19 operating within the guides 15. The upper portion 11 of the upper door section is also provided with arms 20, 21, and 22 which are pivotally mounted

at their upper ends as indicated at 23 in brackets 24 carried by the vertical bars 5 and 6. The upper section of the door formed by the portions 10 and 11 are normally held when the doors are 5 in the closed position by a swinging latch 25 pivotally mounted at one end in the bracket 26 carried by the horizontal bar 3 forming part of the door lintel. The free end of the latch extends 10 over the upper edge of the door portion 11 to engage a keeper 27.

28 are striker members which are carried upon the upper edge of the lower door section 9, the inwardly projecting portion of the striker extending outward so as to engage the inner end of the latch 25 when the lower door section is raised. 15 29 is a stationary cam which is carried by the vertical bars 5^x of the door frame structure in the path of the rollers 19. When the lower door section is raised upward the edge portions thereof 20 travel within the guides 15 in engagement with the rollers 16 and 17 to the intermediate position shown in Fig. 3. When in this position the door may be used for ordinary trucking. By further raising the lower door section the striker 28 engages the latch 25 releasing it from the keeper 27. 25 After this has taken place the rollers 19 engage the stationary cams 29 forcing the upper portion of the lower door section outward, such door section pivoting at its lower end upon the spindles 30 of the rollers 13.

It will be understood when the lower door section is in this position it is tied to the lower portion 10 of the upper door section so that when the roller 19 is forced outward by the cam 29 the portion 10 of the upper door section is carried outward with the lower door section, such portion 10 pivoting upon the spindles of the rollers 14 held in the guideways 8. The parts then assume the position indicated in Fig. 4, the upper portion 11 of the upper door section swinging outward upon the pivots 23 journalled in the brackets 24. By further upward movement of the lower door section 9 and portion 10 of the upper section, the rollers 13 and 14 continue to travel up the guides 7 and 8, the lower door section continuing to swing outward so that the portions 10 and 11 of the upper door section gradually fold together on the hinges 12, finally assuming the position illustrated in Fig. 6 which is the complete open position, the rollers 13 and 14 being then substantially on a line with the horizontal bar 3 of the door lintel.

I will now describe the mechanism by which the doors are raised from the closed to the open 55 position.

30 are brackets which are secured to the vertical bars 5 and 5^x at each side of the door. Each bracket 30 is provided with a bearing support 31 in which is mounted freely an idler pulley 32. 60 33 is a short shaft which is journalled in bearings 34 and 35 carried by the bracket 30 and on which is keyed a pulley 36. 37 is a bevel gear secured to the outer end of the shaft 33. 38 and 39 are horizontal shafts turnably supported adjacent their outer ends in brackets 38^x and 39^x carried by the main bracket 30, one of said shafts being journalled centrally of the door in the bearing 40 mounted upon the vertical bar 6. The adjacent ends of the shafts 38 and 39 are connected together by a coupling sleeve indicated at 41.

42 is a bevel pinion secured to the shaft 38 so as to mesh with the bevel gear 37. 43 is a hand chain pulley operated by the hand chain 44, the pulley being mounted upon the stud shaft 45 car-

ried by the bracket 39^x. 46 is a gear also mounted upon the stud shaft to rotate with the pulley 33 and meshing with the gear 47 secured to the shaft 38. 48 is a counterbalancing weight carrying an idler pulley 49. 50 is a guide pulley mounted on a stud 51 carried by a bracket member 52 secured to the main bracket 30. 53 is a sprocket chain provided at one end with a suitable turnbuckle secured to the spindle of the roller 13. A sprocket chain 53 extends upwardly parallel with each 10 end edge of the door section 9 passing over the corresponding sprocket wheel 36 which is keyed to the shaft 33 from thence downwardly under the idler pulley 49 of the weight 48, then upwardly over the freely mounted idler 32 and from thence 15 downwardly behind the idler 50 to a point of attachment slightly below the centre of the portion 10 of the upper door section as indicated at 54.

The revolving of the hand chain wheels 43 by 20 means of the hand chains causes the shafts 38 and 39 to revolve, the power being transmitted thereto through the bevel gears 37 and 42 and thereby transmitting the hoisting effect to the hoisting mechanism at the opposite side of the 25 door so that such hoisting mechanisms will revolve in unison. By the manual operation of the hand chain the shaft 33 is revolved with the toothed wheel 36. As the upper door section is locked in a stationary position so that it cannot 30 travel upward, the lifting effort is exerted wholly upon the lower door section, the weights 48 serving to counterbalance the lower door section until it is carried to the intermediate position indicated in Fig. 3.

The upper door section is then unlocked by the lower door section so that both the upper and lower sections are free to move upward and the weights 48 then serve to counterbalance the whole door as it is carried from the intermediate position illustrated in Fig. 3 to the final position 40 illustrated in Fig. 6.

It will, therefore, be seen that for a distance of approximately half the height of the opening the lower door section acts in the manner of a 45 straight vertical sliding door. One end of the chain being fixed, the idler sheave on the weights revolves and the weight travels one-half of the distance that the door travels. The total of the weight on both sides is exactly double the 50 weight of the lower door section so that this door section is in perfect balance.

When the upper door section is free as above described during the opening movement of the door both ends of the chain move upward at 55 approximately the same rate of speed therefore changing the action of the weights from a two to one lift to a direct lift. By this means the full weight of the counterbalancing weights is brought into action so as to perfectly balance 60 the weight of the entire door.

As the lower door section is raised past its intermediate position, the upper door section is released and the portions thereof jackknife or fold together so as to lie adjacent the face of the 65 lower door section as such door section approaches the horizontal position.

In order to render the door weather-proof, weather strips 55 and 56 (see Fig. 8) are employed protecting the upper edges of the lower and upper sections, together with the jamb plates 57 which protect the end of the lower door sections. The door may be locked by inserting a pin through the side guides directly above one of the spindles of a roller 13.

When closed the door has nine points of bearing against the door frame formed by the two rollers 13, the two rollers 14, the two latches 25 and the three hinges 12. Doors thus held are not affected by wind pressure and the reactions from wind pressure are distributed evenly to the building superstructure adjacent to the door opening.

What I claim as my invention is:

- 10 1. The combination with a door frame, a door comprising an upper and a lower section having overlapping edge portions, the upper section being divided horizontally into two portions hingedly connected together and swung from the top of the door frame, and means for locking the upper section in a stationary position releasable by the raising of the lower section, of a counter-weighted hoisting device connected to the upper and lower door sections and adapted to change automatically from a two to one hitch to a direct hitch upon the unlocking of the upper section.

2. The combination with a door frame, a door comprising an upper and a lower section having overlapping edge portions, the upper section being divided horizontally into two portions hingedly connected together and swung from the top of the door frame, and means for locking the upper section in a stationary position releasable by the raising of the lower section, of a hoist device comprising a shaft mounted in bearings at right angles to the door frame, a chain gear secured thereto and an idler gear mounted concentrically to the shaft, a weight provided with a traveller pulley, and a chain secured to the bottom of the lower door section and extending upward over the secured gear then down beneath and around the weight traveller and over the idler to the upper door section adjacent the centre of the lower portion thereof.

FREDERICK WILLIAM HALL. 20
